(57) **CLAIM**

The ornamental design for a shower foot rest, as shown and described.

DESCRIPTION

FIG. 1 is a perspective view of a shower foot rest showing my new design.

FIG. 2 is another perspective view of a shower foot rest.

FIG. 3 is a front view of a shower foot rest.

FIG. 4 is a rear view of a shower foot rest.

FIG. 5 is a left side view of a shower foot rest.

FIG. 6 is a right side view of a shower foot rest.

FIG. 7 is a top view of a shower foot rest.

FIG. 8 is a bottom view of a shower foot rest; and,

FIG. 9 is an enlarged view of a shower foot rest taken from the part in FIG. 1.

Any shading is not features of the design but is utilized to illustrate the surface contours of the shower foot rest design in the drawings.

The broken lines illustrate portions of the shower foot rest that form no part of the claimed design.
